ADJUSTABLE ELEVATION POST AND
INSULATOR CONSTRUCTION

Samuel C. Miller, New York, N. Y.

Application December 12, 1940, Serial No. 369,798

6 Claims. (Cl. 248—50)

This application contains subject matter divided from my application Serial No. 337,193, filed May 25, 1940, and is a continuation-in-part thereof.

This invention relates in general to the mounting of luminous gaseous electrical discharge devices, such as the well known neon lights or the like.

More particularly, it relates to means for mounting such tubes on backing or base plates such as customarily used in luminous sign work, in which tubes of various sizes, configurations and collars are assembled on such backings.

In mounting luminous tubes of the character mentioned on such backing plates, it is found that many contrivances for effecting such mounting are inconvenient and ineffective for the purpose because of the labor required in applying them, the lack of adjustability to the many varied contours of the tubes and their tendency to get out of adjustment after they are installed.

It is among the general objects of my invention to overcome the defects of previously known devices for mounting luminous gaseous electrical discharge tubes by the provision of an arrangement for this purpose that is simple, low in cost, effective in use, and convenient to install.

It is among the more particular objects of my invention to provide in a device for the mounting of luminous gaseous discharge tubes on a backing a construction permitting a wide range of adjustability, both laterally and in a direction away from the backing plate, whereby the spacing of the tube from the plate is determined.

It is further among the particular objects of my invention to provide in a device for mounting luminous gaseous discharge tubes on a backing an arrangement whereby a post on which the tube is seated is adjustably mounted in a socket which itself is adjustably mounted on a bracket positioned on the backing plate.

Among the more particular objects of my invention is also the provision of a construction whereby the spacing between a luminous tube and a backing plate may be conveniently controlled between wide limits without the necessity of breaking off portions of the post to which the luminous tube is attached, which breaking off is frequently necessary with devices of this character as heretofore constructed.

It is also among the more particular objects of my invention to provide means for securing a mounting arrangement for luminous tubes to a backing plate, which means may be so associated

with a portion of said arrangement that it can be handled as a unit therewith.

It is still further an object of my invention to provide an elevation post assembly for luminous tubes which will minimize the visibility of metallic elements serving to mount the elevation post assembly upon sign frames or the like, involving a construction which may be simply and economically assembled and constructed.

To attain these objects and such further objects as may appear herein or be hereinafter pointed out, I make reference to the accompanying drawings, forming a part hereof, in which:

Figure 1 is a perspective view showing one illustrative embodiment of my invention with a fragment of a luminous discharge tube mounted in place;

Figure 2 is a perspective view of a detail thereof;

Figure 3 is a front elevational view of another embodiment of my invention showing a fragment of a luminous tube seated thereon;

Figure 4 is a front elevational view of a still further embodiment of my invention;

Figure 5 is a section taken on the line 5—5 of Figure 4;

Figure 6 is a perspective view of a detail of Figure 4;

Figure 7 is a perspective view of an embodiment of the invention illustrated in Figure 2 with another form of bracket;

Figure 8 is an enlarged fragmentary sectional view taken on the line 8—8 of Figure 7, turned in another position;

Figure 9 is a front elevational view of another embodiment of my invention;

Figure 10 is a fragmentary side elevational view thereof;

Figure 11 is a section taken on the line 11—11 of Figure 9;

Figures 12, 13 and 14 respectively, are perspective views of a standard conventional type of post, a socket according to my invention adapted to receive said post and a bracket for use with said socket and post.

Making reference to the drawings, it will be observed that my assembly comprises a post P, a bracket member B and a socket member S. The post P may be of insulating material, preferably glass, comprising a shank 10 having a seat 11, of general V-shaped character, well known in the art. To either side of the seat 11, horns 12 are positioned. The seat 11 serves to receive a luminous sign tube 13. When so positioned, wires 14 may be wrapped around the tube, en-

gaging the horns 12 to hold the luminous sign tube 13 in position.

The bracket B comprises a standard 15, made of wire or like material, one end whereof is bent angularly at 16 and terminates into a loop 17, providing an orifice 18 arranged to receive a screw 19 for attaching the bracket to a frame plate, wall or similar fixed construction.

The socket member S is preferably made from a sheet of spring brass by bending a sheet of such material into a generally S-shaped contour, one loop of the S being enlarged and forming a post P engaging section 19, the other loop being smaller and forming the bracket engaging section 20.

With the socket member S thus provided, the section 19 may be sleeved over the shank 10. The section 20 may be sleeved over the standard 15 of the bracket B. The shank 10 may be circular in cross-section and smooth-faced, in which event the section 19 is formed to give a friction fit, relying upon the resiliency of the metal from which the socket member S is formed to engage the shank 10 of the post P.

Likewise, the standard 15 may be circular and smooth, in which event the section 20 is formed to give a resilient and friction fit to hold the section 20 upon the standard 15 in frictional engagement, relying upon the resiliency of the metal from which the socket member S is formed to provide this frictional engagement.

Additionally, I may provide the standard 15 with a series of indented, circumferentially formed slots 21, in which event the socket member S at the section 20 has the metal thereof indented at 22, to provide a spur on the inner wall of the section 20, arranged to engage the indented slots 21 of the standard 15. Thus, the spur formed by the portion 22 may serve to engage the circumferential slots 21 to increase the frictional engagement of the section 20 in relation to the standard 15 at any predetermined portion along the length of the standard 15. The slots 21 formed on the standard also serve as convenient locations at which the standard 15 may be broken, should it be found that the standard 15 is of an unnecessarily extended length, in connection with the adjustable position desired between the luminous tube 13 and the frame plate to which the bracket B is attached.

In Figure 3 I have illustrated a post P, having a shank 10a, of general circular cross-section, having along its length a series of circumferential slots 21a. In connection with a post having these circumferential slots, I find it desirable to provide the socket S with a detent 22a, thereby projecting a spur serving to engage the circumferential slots 21a formed on the shank 10a and thereby serving to increase the frictional engagement between the socket and the shank 10a of the post.

I may find it desirable to form in the sections 19 and 20, detents in each of the sections, in which event the bracket B may be of the form illustrated in Figure 1, which has the circumferential grooves 21 previously described. Thus, it will be apparent that a post having circumferential slots 21a may be employed, as well as using a bracket B, the standard of which is formed with circumferential slots 21, in which event the sections 19 and 20 both may be formed with detents 22a and 22, respectively.

Where the posts having circumferential grooves 21a and where brackets, the standard 15 of which is formed with circumferential

grooves 21, are employed, it will be understood that a socket member may be employed in which the sections 19 and 20 need not have the detents previously described, and may be smooth walled on the interior, relying upon the resiliency of the material from which the socket S is formed, in connection with the protuberances on the post and standard, respectively, to augment the frictional engagement longitudinally of the post and standard, respectively.

In Figures 4, 5 and 6 I have illustrated another embodiment of my invention.

In this construction, a post P is formed with a screw threaded shank 10b. This may be associated with a bracket B as illustrated in Figure 3, by a socket member S'. The socket member S' is formed from a sheet of spring brass, into generally cylindrical shape, forming a post engaging section 19a. One edge 23 terminates into a pair of loops 24, spaced to each edge of the end 23, outlining orifices 25 adapted to receive the standard 15a of the bracket B. The opposite edge 26 of the section 19a has formed medially thereof a looped portion 27, defining an orifice 28, the diameter of which is such as to receive the standard 15a.

Normally, the socket member S' is distended so as readily to envelop the shank 10b of the post. When placed in the enveloping position, the edges 23 and 26 are then squeezed toward each other, to position the loop 27 in alignment with the loops 24, thereby bringing the orifices 25 and 28 in alignment. In this position, the standard 15a, directed through the orifices 25 and 28, thereby bring the section 19a into frictional engagement with the shank 10b. The normally distended position of the socket S' also serves to cause frictional engagement of the loops 24 and 27 upon the standard 15a, by reason of the oppositely directed tension which the loops 24-24 exert in relation to the loop 27.

While the assembly just described may be employed with a smooth walled post, as illustrated in Figure 10, to achieve a frictional engagement between the socket S and a smooth walled post, I may find it convenient, where employing a post P with a screw threaded shank 10b, to indent the section 19a with detents 22b, the depth of which detents is such as to form spurs on the interior surface of the section 19a, and the direction of which is such as to form a fragmental part of a screw thread complementary to the screw threaded portion 10b of the post P, shown in Figure 4.

Where I use a construction comprising a socket member such as S', illustrated in Figure 6, longitudinal adjustment of this member along the length of the shank of a post P may be obtained by a sliding movement, especially where the shank is smooth.

Where the shank of the post P is formed with a screw-threaded portion 10b, quick location may be effected when the socket member is in the distended position anywhere along the length of the shank of the post.

After aligning the loops 24 and 27 and locking them into position by passage of the standard 15a therethrough, as described, further longitudinal adjustment of the post to the socket member S' may be secured by rotating the post P to effect adjustment by the screw threaded engagement which the detents 22b make in the screw threaded section 10b, as will be readily understood.

In Figures 7 and 8, I have illustrated another

embodiment of my invention which is suitable for use with a socket member S of the character illustrated in Figure 2.

In this construction, a bracket B' is formed with a standard 15b. Along the length of the standard 15b I provide a series of sectional grooves 21e. With such construction, when the bracket B' has the standard 15b inserted in the section 20 of the socket S, the spur formed by the detent 22 will enter the grooves 21e of the standard 15b when in alignment. A partial rotation of the socket S in respect of the post 15b will cause the spur of the detent 22 to rise on the high surface of the standard 15b, as shown in Figure 8, thereby spreading the loop constituting the section 20.

In this position, the socket S may be slid longitudinally of the post 150 without encountering the frictional resistance otherwise present due to an engagement of the spur of the detent 22 with the grooves 21e.

In the embodiment shown in Figures 9 to 14, I have illustrated an arrangement in which a post P', of recognized, standard type, may be used. Such a post is ordinarily made circular in cross section and provided with annular grooves 75, at spaced intervals on its stem or shank portion 10c.

As in the prior embodiment, the upper end of the post P' is provided with horns 16 and a seat 11, adapted to receive a luminous tube. The bracket E may be of a construction identical with the brackets described in my prior filed application and the form illustrated in Figures 1 to 8.

The section 16 may be formed with a loop 17 to receive a screw 19, as already described in connection with Figure 3.

I may find it desirable to provide a screw $11a$, seated within the loop 18 . The fastening element may be provided with a shank having a circumferential groove $11b$, into which the loop 18 is seated. In this form of construction, I provide a socket member S^2 , preferably made of spring sheet metal, such as bronze or the like, defining a standard receiving loop 80 , and a post receiving loop 81 , as obtained by the branches 82 and 83 , leaving a split portion 84 defined by the ends 85 , which are outwardly turned to form camming lips 86 .

The branches 82 and 83 of the section 81 are formed with detents 87, forming spurs 88. These are arranged to enter the grooves 15 on the post P', thereby serving securely to hold the socket S² against longitudinal movement of the post P'.

It will be understood that by this construction, adjustment of the socket S^2 along the length of the post P' is possible only by steps corresponding to the spacing of the grooves 75.

Positioning of the detents 87 at a point intermediate between grooves 75 will serve to spread the branches 82 and 83 of the socket S² and thereby spread the standard engaging portion 80, facilitating slidable movement of the socket S² in respect of the standard 79 of the bracket.

It will therefore be observed that the pressure of the portion 80 on the standard 79 of the bracket is to a great extent independent of any contact between the standard 79 and the shank 10c of the post P', but that the frictional engagement which the section 80 makes with the standard 79 is to some extent dependent upon the relative positions of the branches 82 and 83 to each other.

It will, therefore, be understood that the post-engaging section 80 of the socket S² may be in-

dented to provide a spur, as in the embodiment illustrated in Figures 2 and 7, whereby brackets, such as those described and illustrated in connection with Figures 1 and 7, may be utilized, having complete circumferential grooves 24 or partial grooves 24a, respectively.

partial grooves 21c, respectively. It will be understood that the above construction carries out some of the advantages of the invention of my application Serial No. 337,193, 10 as therein described, permitting the post to be made of definite size and obtaining adjustability of height between the supporting end upon which the neon sign tube rests and the frame.

15 Additionally, my construction minimizes the visibility of the metallic elements serving to mount the glass or insulating elements of the combination. Furthermore, in view of the spatial location of the axial lines through the post engaging section of the socket members herein described, as compared with the axial line through the standard engaging section of the socket member in relation to each other and to the axial line through the loop of the bracket, wherein axial adjustment may be made at three spaced points, I am enabled to achieve adjustability of high magnitude.

It will be readily understood that this feature is highly desirable in view of the intricate contour which luminous signs may be required to assume.

It will be further understood that while in the embodiment illustrated, the most effective results are obtained by combining all of the features illustrated in the combination, it is not intended to be limited to the employment of all of the features so combined, but my invention is regarded as having broader applicability and that segregated portions thereof have novelty per se, and that the invention is to be construed in the light of the appended claims.

Having thus described my invention and illustrated its use, what I claim as new and desire to secure by Letters Patent is:

45 1. In means for mounting luminous gaseous discharge tubes on a backing by an insulating post, a bracket adapted for attachment to the backing including a standard, a socket member having standard engaging portions and post engaging portions, within which portions said standard and post, respectively may pivot, and each of said engaging portions providing pivots for said standard and post, the pivot for said standard lying outside the confines of said post.

50

2. In means for mounting a luminous gaseous discharge tube on a backing, a bracket adapted to be secured to said backing and having a standard, a socket member having a standard engaging portion permitting pivotal movement of the same about said standard, said socket having a post engaging portion formed to engage said post, permitting pivotal movement of said post thereon, said socket member comprising a strip of material S-shaped in cross section, forming spaced loops respectively forming post and standard engaging portions for resiliently and frictionally holding said post and standard, permitting axial adjustment of said post and standard.

3. Means for supporting a luminous gaseous discharge tube in spaced relation to a backing, said means comprising a bracket adapted to be secured to the backing, said bracket having a rod-like portion extending outwardly from the backing when the bracket is secured thereto forming a standard and providing a bearing surface, a post provided with a seat for a luminous tube,

and with a stem portion of circular cross section and having annular grooves thereon at spaced intervals, and a split resilient sleeve having a split cylindrical socket portion adapted to receive and to frictionally grip said rod-like portion of the bracket, and the free end portions of said sleeve being adapted to embrace and frictionally grip the stem of said post, and at least one inwardly directed portion on said free end portions adapted to enter the annular grooves on said stem and hold the stem against axial movement.

4. Connecting means for mounting a luminous discharge tube upon a backing by means of an insulator post adapted to seat said tube thereon, comprising a standard, one end whereof has means to attach the same to the backing for adjustable mounting and a socket member having a standard engaging portion and a post engaging portion, said engaging portions respectively being in non-overlapping planes in respect of the axial line through the standard and post, the standard engaging portion of said socket member outlining a bearing for pivotal movement of the standard therein and of the socket member substantially about the axial line through the standard,

the post engaging portion of said socket member outlining a bearing for axial and pivotal adjustment of the post in respect of said post engaging portion.

5. In means for mounting luminous tubes in accordance with claim 1 in which said post engaging portion of said socket member is a split resilient sleeve and in which said standard engaging portions thereof are spaced apart loops formed on opposite end portions of said sleeve so that when said loops are brought into alignment to receive the standard, the sleeve portion is brought into engagement with said post.

6. Connecting means in accordance with claim 4 in which said post engaging portion of said socket member comprises a split resilient sleeve in a normally distended condition and in which said standard engaging portions are spaced apart loops formed on said sleeve on the end portions thereof defining said split portion, so that when said loops are brought into alignment and the standard passed therethrough the sleeve will be brought into engagement with the post passing through said sleeve.
